UNITED STATES PATENT OFFICE.

GEORGE H. DOWNS, OF PORTLAND, OREGON, ASSIGNOR OF ONE-HALF TO WILLIAM E. GRACE, OF PORTLAND, OREGON.

RUNNING-GEAR FOR ELECTRIC LOCOMOTIVES.

1,006,731.

Specification of Letters Patent. Patented Oct. 24, 1911.

Application filed November 13, 1908. Serial No. 482,479.

To all whom it may concern:

Be it known that I, GEORGE H. DOWNS, a citizen of the United States, and a resident of Portland, in the county of Multnomah and State of Oregon, have invented a new and useful Improvement in Running-Gear for Electric Locomotives, of which the following is a specification, reference being had to the accompanying drawings as constituting a part thereof.

This invention relates to the construction of electric locomotives of the self-generating type, that is to say, which are independent of a trolley wire, or third rail, and, instead, are provided with a primary engine, such, for example, as some type of gas engine, the power of which is applied for driving a dynamo, and the latter generating the electromotive force for driving the wheel-motors. The reason for such conversion of force is the well known fact that all engines which depend upon periodic explosions for their motive power, must be driven at a very high speed, in order to transmit efficient power, and therefore do not allow proper control. But one of the difficulties heretofore met with in the construction of electric locomotives of the class with which my invention is concerned was, the providing of sufficient room for installing the power generating and converting devices, and this difficulty was particularly apparent when the locomotive was required to run on long routes.

Therefore, my invention may be said to have for its general purposes: to provide ample room for all the contrivances required to be assembled within the housing of the locomotive, and to adapt the locomotive to travel easily over the shortest curves of the road. And this invention further has for its object to obtain a running gear which is especially suitable for the particular type of driving means for electric locomotives contemporaneously invented by me, and constituting the subject of another application for Letters Patent.

I achieve the objects enumerated by the combination and arrangement of the parts herein specifically set forth.

In the drawings: Figure 1 is a longitudinal section of a locomotive car-body and

its running gear embodying my invention; Fig. 2 is a longitudinal section, on a larger scale, of the front end of the car-body, and the running gear on which the same is mounted; Fig. 3 is an inverted perspective, on a still larger scale than Fig. 2, of a "bulk-head" which is provided under the car-body at both ends to coöperate with the "chock-blocks" vertically mounted on the front end of each wheel-truck; Fig. 4 is a front elevation of one of said chock-blocks; Fig. 5 is a top view of the wheel-truck shown in Fig. 2, and agreeing in scale with the latter, the superposed car-body of the locomotive being indicated in dotted outline; Fig. 6 is a cross-section on line $x-x$ of Fig. 1, and Fig. 7 is a cross-section on line $y-y$ of Fig. 1; Figs. 6 and 7 being drawn on a larger scale and showing more particularly the cross-section constructed of the frame of the car-body; Fig. 8 is a longitudinal section showing a modification of the construction of my wheel-trucks whereby the locomotive is adapted to run in either direction, without turning the locomotive around; and Fig. 9 is a detail of a removable bar extending across the sliding doors at the sides of the car-body, and constituting a part of the frame thereof.

Referring now to the letters in the several views: The car-body comprises a floor-frame built of girders, and the central portion, a , of the body is dropped below the plane of its two ends a' , a^2 , so as to afford at the middle part of the car-body a larger space, for the accommodation of larger sized dynamos e . The girders of the body-frame are bent down at the center to provide for the drop-floor of the middle portion of the car-body. The girders a^3 at the sides of the car-body on the level of the floors of the body-ends a' , a^2 , do not extend across the enlarged central portion, a , of the car-body, but have connecting parts a^4 , secured by bolts (see Fig. 9) and removable to admit the larger pieces of machinery. The car-body is provided at the sides with sliding doors 17. The removable girder-pieces a^4 , when bolted in place, serve as trusses for the connected ends of the floor girders a^3 .

In the front end of the car-body is provided a space for an oil-tank b , and at the

rear end of the car-body is provided a space for a water-tank *c*. Near the front end of the car the roof is provided with a hood *d*, having windows and serving as the look-out station for the engineer.

f represents gasoline motors driving the motors *e* by chains *g*.

Wheel-trucks *h*, *i*, support the car-body at its ends on pivotal bearings. The wheel-trucks, *h*, *i*, represent a common type of construction, but they have each a projecting portion, *h'*, *i'*, rearward of which the driving wheels are journaled, and under which projecting portion is pivoted a bogie-truck, *j*, *k*, preferably each having four wheels *j'*, *k'*.

Located approximately at the center of the frame of the wheel-trucks is a pivotal or center bearing *l*, of the usual construction, and on such center bearing rests a bolster *m*, which is provided with longitudinally extended bracket-like portions *n*, *n'*, so as to provide an efficient support for the ends of the car-body supported by the wheel-trucks.

At the front end of the frame of each wheel-truck is vertically mounted a chock-block, *o*, a front elevation of which is seen in Fig. 4; and such chock-block is preferably provided with friction-wheels *p*, journaled in cavities therefor provided in the head of the chock-block, the journal-pins *p'* being journaled, at their lower ends, in the body of the chock-block, and the upper ends of the journal-pins being journaled in a plate *q*. Said friction-wheels are of such diameter that the lateral faces thereof will project through the faces of the chock-block, as illustrated in Figs. 4 and 5.

Fastened to the bottom of the car ends, above the chock-blocks, are bulk-heads *r*, which consist of head-plates *s*, each having lateral members *s'*, walls *t*, *t'*, spaced apart so as to provide an intermediate groove into which projects the head or top of the chock-block *o*; and webs, *u*, connect the walls *t*, *t'* with the lateral projections *s'* of the head-plate *s*. The details of said construction are readily observed by having reference to Figs. 2 and 3.

The purpose of the chock-blocks on the wheel-trucks, and the coöperating bulk-heads fastened above the same to the under side of the car-body, is to relieve the strain imposed on the center bearings or pivotal connections of the wheel-truck with the car-body, in case of sudden stops, or collision with obstructions on the track, and reduce the probability of injury of said pivotal connections. The bulk-heads and chock-blocks, in fact, constitute supplemental connecting mediums between the car-body and the wheel-trucks supporting the same by its ends.

The parts shown, but not particularly described, are of the usual construction.

The axles *v* of the driving wheels *w* are journaled in journal-boxes, have vertical play, and are connected by equalizing devices *z*; the construction being substantially the same as that of the standard running gear of steam locomotives.

In the modification shown in Fig. 8, I have shown a wheel-truck which is adapted to be used on locomotives designed to run in either direction, without being turned around on a turn table. The frame of the wheel-truck 20 is made with two projecting ends 20^a, 20^b, under each of which are pivoted bogie trucks 21, 22. And the locomotive, when built of this type, would be provided with a pilot, 23, and a draw-bar, 24, at both ends. Each of the projecting portions 20^a, 20^b is provided with a chock-block *o*, *o'*, of the same construction as above described, and under the car-body there are provided coöperating bulk-heads *r*, *r'*.

In order not to make the wheel-truck of too great a length, only two driving wheels have been introduced in the design of running gear shown in Fig. 8.

I claim:

1. The combination of a car-body having a middle portion, the floor of which is dropped below the plane of the two ends, for the purpose specified, wheel-trucks, and pivotal bearings thereon, supporting the car-body at its ends, a chock-block mounted vertically on the front end of each wheel-truck, said chock-block being curved on a radius of the pivotal center of the wheel-truck, bulk-heads secured under the ends of the car-body, above said chock-blocks, said bulk-heads having grooves curved on the same radius as said chock-blocks, and the latter projecting into said grooves.

2. The combination of a car-body having a middle portion, the floor of which is dropped below the plane of the two ends, for the purpose specified, wheel-trucks, and pivotal bearings thereon, supporting the car-body at its ends, a chock-block mounted vertically on the front end of each wheel-truck, said chock-block being curved on a radius of the pivotal center of the wheel-truck, bulk-heads secured under the ends of the car-body, above said chock-blocks, said bulk-heads consisting of a head-plate, curved pendent parallel walls, spaced apart to provide an intermediate groove, lateral members on the head-plate, and webs connecting said lateral members with said curved walls, said wall-members being curved on the same radius as the chock-block, which projects into said groove of the bulk-head.

3. The combination of a car-body having a middle portion, the floor of which is dropped below the plane of the two ends, for the

- purpose specified, wheel-trucks, and pivotal bearings thereon, supporting the car-body at its ends, a chock-block mounted vertically on the front end of each wheel-truck, said 5 chock-block being curved on a radius of the pivotal center of the wheel-truck, friction wheels journaled in said chock-blocks, the bearing faces of which project beyond the faces of the chock-blocks, bulk-heads secured 10 under the ends of the car-body, above said chock-blocks, said bulk-heads consisting of a head-plate, curved pendent parallel walls, spaced apart to provide an intermediate groove, lateral members on the head-plate, 15 and webs connecting said lateral members with said curved walls; said wall-members being curved on the same radius as the chock-block, which projects into said groove of the bulk-head.
- 20 4. The combination of a car-body having a middle portion, the floor of which is dropped below the plane of the two ends, for the purpose specified, wheel-trucks, and pivotal bearings thereon, supporting the car- 25 body at its ends, said wheel-trucks comprising a frame, driving wheels journaled therein at the rear end of the frame, and a bogie truck and wheels pivoted under the front end of the truck-frame.
- 30 5. The combination of a car-body having a middle portion, the floor of which is dropped below the plane of the two ends, for the purpose specified, wheel-trucks, and pivotal bearings thereon, supporting the car- 35 body at its ends, said wheel-trucks comprising a frame, driving wheels journaled therein at the rear end of the frame, and a bogie truck and wheels pivoted under the front end of the truck-frame, a chock-block mounted 40 vertically on the front end of each wheel-truck, said chock-block being curved on a radius of the pivotal center of the wheel-truck, and bulk-heads secured under the ends of the car-body, above said chock-blocks, 45 said bulk-heads having grooves curved on the same radius as said chock-blocks, and the latter projecting into said grooves.
6. The combination of a car-body having a middle portion, the floor of which is 50 dropped below the plane of the two ends, for the purpose specified, wheel-trucks, and pivotal bearings thereon, supporting the car-body at its ends, said wheel-trucks comprising a frame, driving wheels journaled there- 55 in at the rear end of the frame, and a bogie truck and wheels pivoted under the front end of the truck-frame, a chock-block mounted vertically on the front end of each wheel-truck, said chock-block being curved on a radius of the 60 pivotal center of the wheel-truck, bulk-heads secured under the ends of the car-body, above said chock-blocks, said bulk-heads consisting of a head-plate, curved pendent parallel walls, spaced apart to pro-
- vide an intermediate groove, lateral members on the head-plate, and webs connecting said lateral members with said curved walls; said wall-members being curved on the same radius as the chock-block, which projects into said groove of the bulk-head.
7. The combination of a car-body having a middle portion, the floor of which is dropped below the plane of the two ends, for the purpose specified, wheel-trucks, and pivotal bearings thereon, supporting the car- 25 body at its ends, said wheel-trucks comprising a frame, driving wheels journaled therein at the rear end of the frame, and a bogie truck and wheels pivoted under the front end of the truck-frame, a chock-block mounted vertically on the front end of each wheel-truck, said chock-block being curved on a radius of the pivotal center of the wheel-truck, friction wheels journaled in said chock-blocks, the bearing faces of which project beyond the faces of the chock-blocks, bulk-heads secured under the ends of the car-body, above said chock-blocks, said bulk-heads consisting of a head-plate, curved pendent parallel walls, spaced apart to provide an intermediate groove, lateral members on the head-plate, and webs connecting said lateral members with said curved walls; said wall-members being curved on the same radius as the chock-block, which projects into said groove of the bulk-head.
8. The combination with a car-body and the wheel-truck pivotally supporting the same, of a chock-block mounted vertically on the front end of the wheel-truck, said chock-block being curved on a radius of the pivotal center of the wheel-truck, and a bulk-head secured under the car-body, above said chock-block, adapted to coöperate with said chock-block.
9. The combination with a car-body and the wheel-truck pivotally supporting the same, of a chock-block mounted vertically on the front end of the wheel-truck, said chock-block being curved on a radius of the pivotal center of the wheel-truck, and a bulk-head secured under the car-body, above said chock-block, said chock-block comprising pendent walls curved on the same radius as said chock-block, and being spaced apart, and the chock-blocks projecting between said walls of the bulk-head.
10. In a locomotive comprising a body, the floor at the middle part of which is dropped below the plane of the two ends thereof, doors in the sides of the car-body at the center, and wheel-trucks pivotally supporting the car at its ends, the combination of a floor-frame comprising a series of longitudinal girders dropped at the center of the car-body to a lower plane, and removable girder-pieces arranged on a level with the upper floor level and connecting the floor-girders

of the ends of the car-body, said girder-pieces serving as trusses for the car ends, and being removable so as to clear the whole door openings when required.

5 11. In a car body, the combination of a frame made with a drop center, main trucks pivoted under both ends of the frame, driv-

ing wheels journaled in such trucks, and bogie trucks pivoted at one end of the main trucks.

GEORGE H. DOWNS.
